(57) **CLAIM**

The ornamental design for a shaving razor cartridge connector, as shown and described.

DESCRIPTION

FIG. 1 is a top perspective view of a shaving razor cartridge connector showing my new design;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a back view thereof; and,

FIG. 8 is bottom perspective view thereof.

In the drawings, the evenly-spaced broken lines illustrate portions of the shaving razor cartridge connector forming no part of the claimed design. The dot-dash broken lines illustrate a boundary to the claim and form no part thereof.
